UNITED STATES PATENT OFFICE.

GEORGE A. JOHNSON, OF CHICAGO, ILLINOIS, ASSIGNOR TO WILLIAM H. MINER, OF CHICAGO, ILLINOIS.

DRAFT-YOKE.

1,221,331.

Specification of Letters Patent.

Patented Apr. 3, 1917.

Application filed March 15, 1913. Serial No. 754,530.

To all whom it may concern:

Be it known that I, GEORGE A. JOHNSON, a citizen of the United States, residing at Chicago, in the county of Cook and State 5 of Illinois, have invented a certain new and useful Improvement in Draft-Yokes, of which the following is a full, clear, concise, and exact description, reference being had to the accompanying drawings, forming a 10 part of this specification.

My invention relates to improvements in draft yokes for railway car draft rigging.

The object of my invention is to provide a 15 draft yoke for railway car draft rigging of strong and simple construction, the invention herein disclosed being an improvement upon my invention for which Patent No. 1,038,758 was issued by the United States Patent Office on the 17th day of Sep- 20 temper, 1912.

In the drawings forming a part of this specification Figure 1 is a side elevation partly in vertical longitudinal section on line 1—1 of Fig. 2 of a draft yoke embody- 25 ing my invention. Fig. 2 is a plan view partly in horizontal section on line 2—2 of Fig. 1. Fig. 3 is a perspective view of one of the free ends of the yoke strap.

In the drawings 4 represents a U-shaped 30 yoke strap having upper and lower limbs 5 and 6 respectively, and a member 7 connecting the same at their rear end. In preferable construction within the yoke strap at its rear end there is provided a filler block 35 8 secured to the member 7 by means of the rivet 9. The forward end of each limb of the yoke strap is provided with a laterally extended and outwardly turned head 10 of T-shape, forming a transverse shoulder 11 and shoulders 12, 12 at either side of each 40 limb of the yoke strap.

13 represents a hollow yoke head or hood having an opening 14 therein adapted to receive a draw bar, the said yoke head being 45 formed of lateral plates 15, 15, and top and bottom plates 16 and 17 respectively joining the same. The yoke head is also provided with slots 18, 18 through the lateral plates thereof to receive a coupler key 19, which 50 passes through the same and through the transverse opening 20 in the draw bar 21.

In assembling the U-shaped yoke, the strap 4 and the yoke head 13 I pass the said 55 yoke strap rearwardly through the opening 14 in the said head until the shoulders 11

of the upper and lower strap heads 10 engage the forward edges 22, 22 of the upper and lower plates 16 and 17 respectively of the yoke head, and the shoulders 12 of the strap head engage the front edges 23, 23 of the lateral plates 15 of the said yoke head. The limbs 5 and 6 of the yoke strap are suitably spaced apart to permit the reception between them of the draw bar 21 within the box-like opening 14 of the yoke head 13. 60

By referring to the drawing, it will be observed that the lateral or side plates 15 of the hollow yoke head are extended or provided with forwardly projecting wings 120, the upper and lower forward edges 70 121 and 122, respectively, of said wings being suitably inclined to engage the inner faces 123 of the T shaped heads 10 of the yoke strap, to thus prevent the forward ends of the yoke strap from approaching 75 each other under the strain of pulling movement of the draw bar and binding the draw bar between the limbs of the yoke. It will also be noted that the side or lateral plates 15 are flared outwardly in order to provide 80 sufficient clearance between the draw bar and said plates to permit the draw bar to swing laterally or radially relatively to the yoke.

I claim:—

1. In a yoke for draft rigging for railway cars, in combination, a yoke head adapted to be connected to a draw bar, and a yoke strap, said yoke strap being provided at each of its free ends with a T head engaging the yoke head, the said yoke head having forwardly extended lateral plates adapted to engage the inner faces of said T heads. 85

2. In a draft gear yoke, in combination, a hollow yoke head having top, bottom and side walls and open ends, the side walls being extended forwardly beyond the top and bottom walls, and a strap, the ends of said strap extending through the yoke head, each end being widened and thickened to form a T head and a rearwardly facing transverse shoulder with the arms of the T head adapted to engage said extended portions of the side walls of the yoke head, and the said transverse shoulders abutting against the forward edges of the top and bottom walls of the yoke head. 95

3. In a draft yoke, in combination, a U shaped loop having lateral projections at 110

the ends of its side members, and a hollow, rectangular draw bar engaging member adapted to surround the draw bar and having forwardly facing shoulders for engaging said projections.

4. In a draft gear yoke, in combination, a yoke head having top, bottom and side walls, the side walls extending forwardly of the top and bottom walls and being of 10 less vertical height than the distance between the top and bottom walls, a U shaped strap having its ends extended through the yoke head and being provided with lateral extensions bearing against the forward 15 edges of the top and bottom walls of the yoke head and adapted to engage the edges of the forwardly extended portions of the side walls of the yoke head.

5. A yoke for draft riggings comprising 20 a U shaped strap having the ends of the arms thereof provided with laterally extended shoulders and a hollow yoke head

having shoulders coöperable with the shoulders of said arms, the yoke head being assembled with the strap by sliding the one 25 longitudinally of the other.

6. A yoke for draft riggings comprising a hollow cast head adapted to be detachably connected with a draw bar, and a strap extending through said hollow head, the arms 30 of said strap having the free ends thereof provided with T heads arranged to engage the yoke head.

7. A yoke for draft riggings comprising a U shaped strap, the free ends of the arms 35 thereof being provided with laterally extended and transverse shoulders, and a hollow yoke head surrounding the yoke strap and having shoulders coöperating with said lateral and transverse shoulders of the strap. 40

GEORGE A. JOHNSON.
